UNITED STATES PATENT OFFICE.

ROBERT E. SHEAL, OF CLEVELAND, OHIO.

MOVABLE BRIDGE.

Application filed September 10, 1924. Serial No. 736,819.

This invention relates to movable bridge structures such as those used for handling and transporting bulk material, examples of which are stocking bridges, unloading machinery, and the like. These devices are generally of very great size and weight, and frequently, particularly ore bridges and stocking bridges, project to a very considerable height and exhibit a very large surface to the wind as well as being generally situated on docks and in other exposed positions where the full force of the wind is developed. The objects of my invention are the provision of improved mechanism for propelling such structures along their runways when desired and at other times locking the same against any possible movement as a result of wind pressure; the provision of a propelling and securing unit applicable to structures of diverse designs, either already existing or hereafter erected according to the plans of different designers; the provision of a rack drive consisting of a unit mechanism applicable to structures not originally designed therefor; the provision of mechanism of the character described which shall be maintained in operative relation with the driving rack more accurately than other devices; while further objects and advantages of the invention will become apparent as the description proceeds.

In the drawings accompanying and forming a part of this application I have illustrated certain physical forms in which my inventive idea can be embodied although it will be understood that these drawings are intended merely to illustrate the principles of my invention and not to restrict me to the details of construction. Fig. 1 is an end elevation of a typical stocking bridge equipped with my improvements; Fig. 2 is a plan view of the driving mechanism, the housing being shown in section; Fig. 3 is a right hand elevation of the mechanism shown in Fig. 2, the housing being likewise shown in section; Fig. 4 is a left hand elevation of the mechanism, the housing being shown in section; Figs. 5 and 6 are sectional views corresponding to the lines 5—5 and 6—6 respectively of Figs. 2 and 3 and looking in the direction of the arrows; and Fig. 7 is a detail view corresponding to the line 7—7 of Fig. 3.

Movable structures of the type herein described generally comprise a truss or body

portion 1 supported at its ends upon upright towers indicated generally at 2, each tower being supported by means of a large number of suitable wheels 3—3 on a suitable runway. The truss or body portion of the bridge may be of any length and design, being here shown merely in end elevation; the "towers" may comprise either a single panel or a plurality of panels or legs; and any suitable type of wheels and runways may be employed, that here shown comprising flanged wheels running on standard T rails 4 fastened to cross ties 5. Each leg or panel of such tower ordinarily terminates at its lower end in a pair of spaced horizontal sill girders 6—6 formed with suitable provisions indicated at 7—7 in Fig. 6 for the reception of the bearings for the supporting wheels. Owing to the great weight of the structures, it is quite common to find as many as thirty-two such wheels located beneath a single leg, although my improvements are independent of the number.

My invention comprehends a driving device built as a unit and operatively secured to these girders, preferably at one end thereof, and carrying a massive pinion meshing with a suitable rack located along the runway. In its preferred form this unit comprises a rigid frame consisting of spaced parallel side members 10—10 secured together by suitable cross members 11, 12, 13, 14 (only a few of them have been indicated), interposed between the girders 6—6 at one end thereof and pivoted thereto upon a massive horizontal pivot pin 15; the other end of the frame being supported by carrying wheels 16—16 engaging the runway. In this embodiment the wheels 16—16 run on the same rails 4 which support the carrying wheels 3. The wheels 3 are located between the girders 6, 6, with their bearings at the outside of the wheels as customary in railroad trucks (see Fig. 6) and in my unit the frame 10 is preferably located between the wheels 16—16, thus enabling easy attachment of the frame to the girders while permitting its own wheels to run upon the same tracks, thereby automatically adjusting the height thereof above the rack 17 which is mounted on the runway preferably between the rails 4—4. The lower edges of the members 10—10 are arranged to clear the axles of the carrying wheels as shown in Fig. 3. The free ends of the girders 6 are preferably stiffened by

means of a cross pin 18 rigidly bolted thereto at its ends and passing loosely through holes 19 of larger size formed in the members 10.

Carried by these members are suitable supports 20 in which is carried a horizontal shaft 21 on which is mounted a massive pinion 22 which meshes with the rack 17. The upper edges of these members also carry suitable mechanism for operating this pinion, one of the best forms I have so far conceived comprising a horizontal shaft 23 mounted in suitable bearings 24 and carrying a driving gear 25 meshing with the pinion and a driven gear 26. I have found it very satisfactory to make the gear 25 in the form of a shrouded gear and fasten the gear 26 directly thereto. I have shown the gear 26 as meshing with a smaller pinion 27 sleeved on a horizontal bar 28 clamped in suitable supports 29, this gear being operatively connected to a worm gear 30. In the present embodiment I have shown the pinion 27 as formed integral with a sleeve 31 to which the gear 30 is tightly keyed, thus increasing the strength of the mechanism.

Mounted beneath the worm gear 30, longitudinally of the frame is a worm shaft 32, here shown as provided intermediate its length with a flexible coupling 33, one end being journaled in a bearing 34 and the other end being supported in the bottom section 35 of the gear casing, here shown as held in place by a cross member 36 carried by the sills 10-10. One end of this worm shaft is provided with a worm 37 meshing with the worm-gear 30 and the other end with a spur-gear 38 meshing with a companion gear 39 carried on the armature shaft of an electric motor 40. This motor is mounted longitudinally of the frame and carried by the cross pieces 13 and 14. The gears 38, 39 have the advantages of permitting a certain amount of flexibility in the alignment, compensating for the speeds of different motors or different current conditions, and of permitting the ready unshipping of the motor for purposes of repair. While size is not an essential part of the invention the mechanism is generally very massive, the pinion 22 here-in illustrated being approximately five feet in diameter, and a 100 h. p. motor being employed. The rack is of similar massive construction in this embodiment comprising steel cross pins four inches in diameter and eighteen inches long, and steel side members two inches thick and nine inches high. This rack can be anchored to the runway in any desired manner, but preferably in the manner described and claimed in my Patent No. 1,435,341, issued November 14, 1922.

For stopping the operation of the mechanism and holding the structure against accidental movement I have shown a brake drum 42 carried by the end of the worm shaft 32 and provided with suitable brake

shoes 43-43 released by a solenoid 44 through the agency of a brake lever 45, and set automatically by weights or springs when the current is cut off. The setting action is retarded by a dash pot 46 connected to the brake lever by a compound lever 47. In practice the weight to set the brake is largely furnished by the lever 45 and solenoid plunger, and associated parts.

The entire mechanism is preferably sheltered in a metal housing comprising vertical sides 50, 51 and a slant top 52, suitably removable panels 53 being provided to afford access to the mechanism.

One rack and one unit is employed in connection with each runway. The motors are of a reversible type and are often controlled from a distance. The brakes are normally held in tight contact with the brake drum by means of springs or levers as described above so that the friction produced thereby, coupled with the high mechanical advantage of the worm drive, may hold the structure against even the most sever wind pressure. The solenoid 44 is connected in series with the motor circuit in such wise that upon starting the motor the brakes will be automatically released and upon turning off the current from the motor the brakes will be automatically reset. The armature shaft is preferably provided with a fly wheel 48 to prevent the stoppage of the mechanism with such abruptness as to injure the moving structure.

It will be understood that a great many changes in point of detail, construction, design, and arrangement of parts can be made within the scope of my invention. I do not limit myself to the location of my improved unit at the ends of the girders; I do not limit its location to a point between the carrying tracks as it can be located between adjacent pairs of tracks where the same are not too far separated, or along side a single track in the case of certain unloading machinery. I do not limit myself to forming the rack fully independent of the carrying rails nor in any other way except as specifically recited in my several claims which I desire may be construed each without reference to limitations contained in other claims.

Having thus described my invention what I claim is:

1. The combination with a movable structure having a tower and a truss, of supporting wheels carried by said tower, a runway for said wheels, a rack along said runway, and a propelling and securing unit structurally independent of said tower and operatively secured thereto, said unit comprising a pinion meshing with said rack and an irreversible driving mechanism for said pinion, said mechanism including a worm gear.

2. The combination with a movable structure having a tower and a truss, of support-

ing wheels carried by said tower, a runway for said wheels, a rack along said runway, and a propelling and securing unit structurally independent of said tower and operatively secured thereto, said unit comprising a pinion meshing with said rack, driving mechanism for said pinion, including a worm gear, and braking mechanism on the worm side of said driving mechanism.

10. 3. The combination with a movable bridge tower of the type having a pair of spaced parallel sill girders, supporting wheels beneath said girders and a runway for said wheels, of a rack along said runway, and a frame projecting between said girders and pivoted thereto, said frame having supporting wheels engaging said runway and a pinion engaging said rack and mechanism for driving and restraining said pinion, said

mechanism comprising an irreversible worm 20 drive and a fly wheel.

4. The combination with a movable bridge tower of the type having a pair of spaced parallel sill girders, supporting wheels beneath said girders and a runway for said 25 wheels, of a rack along said runway, and a frame located beyond said wheels and projecting between said girders and coupled thereto, supporting wheels carried by that portion of said frame which projects beyond 30 said girders, said last named wheels engaging said runway, a pinion journaled to said frame and engaging said rack, and means carried by said frame for starting and stopping and controlling said pinion. 35

In testimony whereof, I hereunto affix my signature.

ROBERT E. SHEAL.
